Primary Examiner — Ricky Pham(74) *Attorney, Agent, or Firm* — Howard & Howard Attorneys PLLC(57) **CLAIM**

An ornamental design for a cabinet, as shown and described.

DESCRIPTION

FIG. 1 is a perspective view of a cabinet in accordance with the present invention;

FIG. 2 is a top plan view of the cabinet;

FIG. 3 is a front elevational view of the cabinet;

FIG. 4 is a bottom plan view of the cabinet;

FIG. 5 is a left side elevational view of the cabinet;

FIG. 6 is a right side elevational view of the cabinet;

FIG. 7 is a rear elevational view of the cabinet;

FIG. 8 is an enlarged front elevational view, identical to FIG. 2, of the cabinet where a front design pattern is more clearly visible; and,

FIG. 9 is an enlarged portion of the front design pattern of the cabinet.
